UNITED STATES PATENT OFFICE.

SAMUEL FRIEDMAN AND MAX OHLBAUM, OF NEW YORK, N. Y.

FIBER COMB.

1,405,576.

Specification of Letters Patent. Patented Feb. 7, 1922.

Application filed March 12, 1921. Serial No. 451,926.

To all whom it may concern:

Be it known that we, SAMUEL FRIEDMAN and Dr. MAX OHLBAUM, citizens of the United States, residing at New York, in the county 5 of New York and State of New York, have invented certain new and useful Improvements in Fiber Combs, of which the following is a specification.

This invention relates to fiber combs, the 10 object thereof being to provide an improved article of this type which will be serviceable in use and which may be manufactured and produced at a minimum of expense.

Due to the fact that there is always a large 15 demand for cheap and sanitary combs for use in public places, and which after use may be thrown away or destroyed, thus doing away with the so-called "public combs" used over and over again and which are recognized 20 as unsanitary and unhealthy, the essential purpose and object of our improvement is to provide an inexpensive but sanitary article which may be used in quantities in public lavatories without great expense. 25 The necessity of having to use a comb previously used by other persons will thereby be avoided.

Other objects of our invention will appear 30 in the following description thereof, reference being had to the accompanying drawing forming a part of this specification, wherein like reference characters indicate corresponding parts in the several views and wherein Fig. 1 is a plan view illustrating a 35 blank for a comb; Fig. 2, shows an enlarged cross-section thereof; Fig. 3 is a side view illustrating in part a completed comb; Fig. 4 is an enlarged section as on line 4—4 of Fig. 1; and Figs. 5, 6, and 7 show modified 40 forms thereof.

In its preferred form herein shown and described we provide a comb stamped from a blank sheet 5 composed of a material that is practically waterproof without any special 45 treatment of its surfaces. One such material is fiber or other relatively dense non-porous material, such as insulating fiber. In practice the fiber sheets are treated during their preparation with some suitable preparation 50 or substance so that the sheets are waterproof. The comb 6 is stamped or cut out from the blank 5 and is thereupon ready for immediate use without necessitating the application of varnish or the like, or the impregnation of the surfaces with waterproofing material. The treatment of the raw ma-

terial before completion of the blank sheet renders this extra step unnecessary. The blank may comprise if desired several layers, 8 and 9 of fiber stock, intimately and integrally associated, during the manufacture thereof, as illustrated in Fig. 4, without the need of any intervening substance to stick or retain the layers together, the construction of the blank being such that a comb of great 65 durability, strength, and sufficient rigidity is obtained, thus resulting in a very practical and efficient expendable article.

Heretofore all sanitary combs of the present general type which have been put on the 70 market have been so expensive to manufacture that the very object for which they are designed, namely, the provision of a very cheap, but satisfactory article, has been prevented. In order to make a comb such as 75 this successful commercially, it is absolutely necessary that every unessential step be eliminated from the process of manufacture. It is recognized that there are two important requisites of a sanitary comb, namely 80 that it be manufactured of cheap material, and as a finished product be sufficiently waterproof to render the same impervious to the deleterious effects of water.

Heretofore one of the main disadvantages 85 of sanitary combs, made from paper, cardboard, or other relatively porous stock resides in the necessity of treating the finished article with a suitable preparation to render the same impermeable, such process being 90 comparatively expensive and thus an obvious commercial drawback. For instance it has been attempted to make sanitary combs from paper, cardboard, or papier mâché, the blanked article being coated, varnished, shellacked, or otherwise treated after the completion of the comb in order to render the same impervious to the effects of moisture. This coating or impregnating of the surface 95 of the comb has been found to be a commercial disadvantage due to the comparatively great expense incident thereto.

Thus by virtue of our invention these disadvantages are done away with, and we accomplish the same by constructing a comb of 105 fiber or other relatively dense and non-porous substance such as is often employed for instance in the production of insulating materials and which raw material prior to the blanking out of the comb is preferably treated in any suitable way thereby to render the finished article thoroughly impermeable 110

and waterproof. The waterproofing chemical or material is incorporated in the fiber pulp, and hence the fiber sheets formed from the pulp are thereby rendered thoroughly 5 waterproofed by virtue of this chemical treatment. Thus after the fiber or material to be used for making the blanks is treated with such preparation and after the formation of the blank sheet, the comb may 10 be stamped out by means of suitable dies, or otherwise formed therefrom. The completed comb is then ready for use and it will be seen that by means of this simplified process, the separate step of varnishing, 15 shellacking, coating, or impregnating is entirely eliminated and therefore it will be obvious that the ultimate cost of our completed comb will be very materially reduced. By virtue of the fact that the raw material or 20 fiber from which the blank is produced for stamping out the comb, is usually first treated in the manner above indicated, the completed comb therefore will be more effectively impervious to the effects of moisture 25 and hence in a single step we accomplish what has hitherto required at least two steps, and at the same time our improved sanitary comb made from cheap fiber is manufactured at a greatly reduced cost.

30 In order to secure an increased rigidity or stiffness in our improved sanitary comb, the same may be readily accomplished by providing the comb 6, as illustrated in Fig. 5, with a groove 10 of any suitable length, 35 width, and depth, the same being effected as by stamping or compressing a portion of the comb to form the groove. Or the comb may be reinforced by providing a corrugation or ridge 11 as shown in Fig. 6 comprising a

depression on one side and a bulging or 40 ribbed portion on the opposite side of the comb. In this manner therefore the comb is readily, inexpensively, and integrally reinforced or stiffened without necessitating the use of a separate or independent strip of 45 metal or other material, the comparative cost of which method would do away with the essential purpose of my invention; namely to provide a cheap but efficient comb.

Although we have described our invention 50 in its preferred form, it is to be understood that we do not limit ourselves to the present preferred embodiment herein shown and described, except in so far as defined in the claims and embraced within the scope 55 thereof.

We claim as our invention:

1. As an article of manufacture a comb cut from a blank having non-coated surfaces impervious to moisture, said comb having an 60 outer surface provided with a lengthwise extending depressed portion.

2. As an article of manufacture, a comb stamped from a blank of fiber treated with a waterproofing substance prior to the completion of the blank, thereby to render the surfaces of the comb substantially impervious to the effects of moisture.

3. As an article of manufacture, a comb formed from a blank of waterproofed fiber 70 material, said comb being so formed as to have the surfaces thereof substantially impervious to moisture without necessitating the coating of the surfaces.

Signed at New York city this 17th day 75 of February, 1921.

SAMUEL FRIEDMAN.

MAX OHLBAUM.
